TRANSLUCENT BOTTOM HANDBAG

Gertrude B. Hume, Claremont, Calif.

Application August 31, 1942, Serial No. 456,742

6 Claims. (Cl. 150—28)

This invention has to do generally with improvements in bags, purses and the like, particularly ladies' handbags, and has for its major object to provide novel features of construction permitting illumination and clear visibility of the interior of the bag and its contents.

A common experience is that articles in the bottom of the bag cannot easily be found or identified because of the dark interior of the bag, occasioned by its depth and the fact that bags are made of leather, fabrics or other opaque materials, permitting no passage of light into the bag except through its open top. I have discovered an effective, yet extremely simple means whereby the entire contents of the bag may be illuminated to a degree of clear visibility, without complicating the form and construction of the bag, and without affecting its desirable appearance.

This objective may be accomplished by making the main body portion of the bag of an opaque material, leather for example, to give desired texture, color and general appearance, and incorporating in the bag a translucent portion or wall, through which light passes in such relation to the bottom contents of the bag as to render them clearly visible through the top of the bag when opened. Preferably I use in the bag construction a translucent piece that ordinarily is substantially concealed, as by causing it to be positioned or folded back between opaque side portions of the bag.

In a preferred, though typical form of the invention, the bag is made to comprise opaque side portions interconnected at the bottom, by a translucent expansion section. The latter may be transparent, or opaque to a limited degree rendering the material capable of passing the necessary light. Preferably the translucent piece will be opaque to a degree preventing the bag contents from being identified from the outside. By forming the bottom of translucent material, light is permitted to enter the bag through its bottom, thus placing the bag contents directly between the light source and the vision of one looking into the bag. It may be desirable to use a flexible translucent material which can be formed and flexed as a single expansion piece, or used in sections interconnected by a flexible joint or hinge. Otherwise, the bottom of the bag can be made simply of a single relatively flat piece. Typical of suitable translucent materials are cellulose acetate, chlorinated synthetic rubber base, and various other synthetic translucent, flexible sheet materials now available, any of

which may carry pigments or other substances giving the material some opacity.

The invention will be understood and explained to better advantage by reference to the accompanying drawing illustrative of the invention in certain typical and preferred forms. In the drawing:

Fig. 1 is a side elevation of a bag having a translucent bottom expansion piece;

Fig. 2 is a perspective view showing the end and bottom expansion pieces;

Fig. 3 is a bottom view;

Fig. 4 is a similar bottom view illustrating a variational, hinged form of translucent expansion piece;

Fig. 5 is an enlarged fragmental view partly in section taken on line 5—5 of Fig. 4; and

Fig. 6 is a similar view showing the translucent wall in the form of a substantially flat bottom piece.

The form of bag illustrated is shown to be of a usual design, comprising opaque side portions 10 of leather or other commonly employed material interconnected at their ends by inwardly folded expansion pieces 11. Such bags may have opaque bottoms or bottom expansion pieces, and are of such depth that the bottom contents, when viewed by opening the top 12, are not clearly visible because of the dark interior of the bag.

In accordance with the invention, the bottom 13 of the bag is made of translucent material of the character referred to hereinabove, and according to the forms shown in Figs. 1 to 5, is constructed as an expansion piece formed by bending the translucent sheet 14 inwardly along a fold 15. The edges of the material 14 may be suitably secured, as by sewing or taping at 16 to the bottom edges of the sides 10 and at 17 to the end expansion pieces 11. The translucent material 14 may have sufficient inherent flexibility as to resist splitting along the fold 15, or along the seams 16 and 17, under condition of usage and of wear.

In the form of the invention shown in Figs. 4 and 5, the bottom translucent expansion piece 18 is made in sections 19 and 20, secured to the sides 10 and end expansion pieces 11, and interconnected at 21 by a suitable hinge. As shown in Fig. 5, the hinge may consist of a fabric strip 22 sewed or taped to the sections 19 and 20, thus causing the hinge material to assume the bottom flexure as the sides of the bag are collapsed or spread apart, instead of such flexure being taken by the translucent material itself.

Fig. 6 illustrates the use of a bottom trans-

lucent section 25 lacking the expansion characteristics of the above described forms, in that the section is relatively flat and maintains a uniform spread of the sides of the bag. As shown, section 25 may be set back at 26 sufficiently from the bottom edges of the sides to favor concealment of the bottom material.

As will be apparent, the translucent bottom permits direct entry of light to the bottom of the bag, illuminating its contents and placing the articles therein directly in an illuminated line of vision through the open top of the bag. As a result, the contents of the bag, or individual articles therein, can be clearly seen and found without difficulty. Also it will be observed that in normal usage of the bag, its bottom section will not be apparent in any way to detract from the desired appearance of the bag.

I claim:

1. A bag of the character described adapted to be opened at its top, said bag comprising substantially opaque sides, and a translucent section between said sides and passing sufficient light to clearly reveal the contents of the bag when viewed through its open top, said section being opaque to a degree preventing visual identification of the bag contents when viewed from the outside through said section.

2. A bag of the character described adapted to be opened at its top, said bag comprising substantially opaque sides, and a normally inconspicuous translucent bottom section between said sides and passing sufficient light to clearly reveal the contents of the bag when viewed through its open top.

3. A bag of the character described adapted to be opened at its top, said bag comprising substantially opaque sides, and a normally inconspicuous translucent flexible expansion section between and allowing spreading apart of said sides, said expansion section passing sufficient light to clearly reveal the contents of the bag when viewed through its open top.

4. A bag of the character described adapted to be opened at its top, said bag comprising substantially opaque sides, and a normally inconspicuous translucent flexible expansion section forming the bottom of the bag and permitting spreading apart of said sides, said expansion section passing sufficient light to clearly reveal the contents of the bag when viewed through its open top.

5. A bag of the character described adapted to be opened at its top, said bag comprising substantially opaque sides, and a normally inconspicuous translucent and substantially flat section forming the bottom of the bag and passing sufficient light to clearly reveal the contents of the bag when viewed through its open top.

6. A bag of the character described adapted to be opened at its top, said bag comprising substantially opaque sides, and a translucent bottom section between said sides and passing sufficient light to clearly reveal the contents of the bag when viewed through its open top, said bottom piece being opaque to a degree preventing visual identification of the bag contents when viewed from the outside through said section.
